DESIGN FOR A DISHCLOTH HOLDER

Therese M. Sabo, Los Angeles, Calif.

Application October 20, 1947, Serial No. 142,014

Term of patent 14 years

(Cl. D44—29)

To all whom it may concern:

Be it known that I, Therese M. Sabo, a citizen of the United States, residing at Los Angeles, in the county of Los Angeles, in the State of California, have invented a new, original, and ornamental Design for a Dishcloth Holder, of which the following is a specification, reference being had to the accompanying drawing, forming a part thereof.

Fig. 1 is a side elevational view of a dishcloth holder, showing my design; Fig. 2 is a front elevational view of the same; and Fig. 3 is a rear elevational view of the same.

I claim:

The ornamental design for a dishcloth holder, as shown.

THERÈSE M. SABO.
